UNITED STATES PATENT OFFICE

SAMUEL E. BOUCHARD, OF ROCHESTER, NEW YORK, ASSIGNOR TO BAUSCH & LOMB
OPTICAL COMPANY, OF ROCHESTER, NEW YORK, A CORPORATION OF NEW YORK

DESIGN FOR A COMBINED ENDPiece AND TEMPLE FOR SPECTACLES

Application filed April 28, 1933. Serial No. 47,905. Term of patent 7 years.

To all whom it may concern:

Be it known that I, SAMUEL E. BOUCHARD, a citizen of the United States, and a resident of Rochester, county of Monroe, and State of New York, have invented a new, original, and ornamental Design for a Combined End-piece and Temple for Spectacles, of which the following is a specification, reference being had to the accompanying drawing, forming a part thereof.

Fig. 1 is a perspective view of a combined

endpiece and temple for spectacles embodying my new design.

Fig. 2 is a sectional view taken on line 2—2 of Fig. 1.

Fig. 3 is a sectional view taken on line 3—3 of Fig. 1.

I claim:

The ornamental design for a combined end-piece and temple for spectacles substantially as shown.

SAMUEL E. BOUCHARD.
